UNITED STATES PATENT OFFICE.

JOHN H. SCHUSSLER, OF CHICAGO, ILLINOIS.

VIBRATING DISTRIBUTING-ROLLER FOR PRINTING-PRESSES.

1,282,957.

Specification of Letters Patent.

Patented Oct. 29, 1918.

Application filed August 13, 1917. Serial No. 185,883.

To all whom it may concern:

Be it known that I, JOHN H. SCHUSSLER, a citizen of the United States, and resident of Chicago, in the county of Cook and State of Illinois, have invented certain new and useful Improvements in Vibrating Distributing-Rollers for Printing-Presses, of which the following is a specification.

This invention relates in general to printing presses and more particularly to improved means for distributing ink upon the inking rolls of a platen press.

In order that the inking rolls of printing presses may apply ink to the printing surface evenly and uniformly, it is desirable that means should be provided for distributing the ink smoothly over the rolls. By providing such ink-distributing means a higher grade of work may be done and greater speed attained owing to the more uniform application of the ink to the printing surface.

The main object of my invention is to improve means whereby ink may be applied or distributed uniformly and smoothly to inking rolls during the entire movement thereof relatively to the inking disk and printing surface.

Another object of my invention is to simplify and improve the mechanism for reciprocating or vibrating the distributing roll with respect to the inking rolls.

Another object is to provide ink-distributing means for the inking rolls of a press adapted to meet the various requirements for successful commercial operation.

Generally speaking, these and other objects are accomplished by providing in a printing press the combination of an inking roll, a distributing roll engaging the surface of said inking roll, and means for yieldably and adjustably holding said rolls in contact with each other, and novel means for reciprocating the distributing roll with respect to the inking roll.

The invention is illustrated on the accompanying sheets of drawings, in which:

Figure 1 is a fragmentary side elevation of a platen printing press embodying my invention;

Fig. 2 is a fragmentary front elevation of the same;

Fig. 3 is a fragmentary detail end elevation of the two inking rolls and distributing roll shown in accordance with my invention and on a larger scale than shown in Fig. 1;

Fig. 4 is a fragmentary front elevation of the same;

Fig. 5 is a detail fragmentary side elevation of the single inking roll with the distributing roll held in engagement therewith in accordance with my invention and shown on a larger scale than shown in Fig. 1;

Fig. 6 is a fragmentary front elevation of the same; and

Fig. 7 is a sectional view taken in the plane of line 7—7 of Fig. 4.

The various novel features of my invention will be apparent from the following description and drawings and will be particularly pointed out in the appended claims.

By referring to Figs. 1 and 2 of the drawings, it will be noted that I have shown a platen printing press 10 including side frame members 11 and 12, at the upper end of which is supported a disk 13 having an ink supplying surface. A printing surface 14 is located below and in front of the disk 13. A pair of inking rolls 15 is arranged to move over the inking surface of the disk 13 and also over the printing surface 14, said inking rolls 15 being engaged by one or more sections of a distributing roll 16. I have also shown another inking roll 17 which is adapted to move over the inking surface of the disk 13 and over the printing surface 14. This inking roll 17 is engaged by another distributing roll 18.

Hook members 19, each having oppositely arranged hooks 20 at opposite ends of the inking rolls 15, fit over the reduced end portions of said rolls and yieldingly press said rolls into engagement with the disk 13 and printing surface 14 by the usual rod and spring mechanism 21, the rod being connected to the hook member at a point 22. Similarly a hook member 23 passes around the reduced ends of the inking roll 17 for a similar purpose, the roll 17 being yieldingly held in contact with the inking and printing surfaces by the usual spring mechanism 24. The carriage 25 is pivoted at 26 in the usual manner.

The distributing roll may be in one section or be made up in two sections, as shown in Fig. 2, or if desired there may be more sections. Where there are two or more sections they are separated by a collar 27, which collar and also the sections are mounted over a shaft 28, which is adapted to be reciprocated or vibrated axially or transversely of the machine and along the

length of the inking rolls 15. The distributing roll 16 is secured to the shaft 28. As shown in Fig. 2 of the drawings, I have shown two sections. It will be noted that 5 immediately to the left of the left-hand section there is provided a collar 29 which is keyed to the shaft 28. The left-hand section of the ink-distributing roll engages the collar 29, the intermediate collar 27 being 10 tightly pressed between the left and right-hand sections, and to the right of the right-hand section of the distributing roll there is provided a collar 30 which is secured to the shaft by a set-screw. In this manner 15 the sections are maintained rigid with the shaft 28.

It will be noted that the left-hand end of the shaft 28 is provided with a threaded portion 31 which passes through and meshes 20 with a coöperating internal threaded portion 32 (see Fig. 7) of a bushing 33. This bushing 33 is supported in a bracket 34 which in turn is secured to the hook members 19 by set-screws 35. Between the sides 36 of 25 the bracket 34 is secured a pin 37 to which is pivoted a resilient member 38 having a semi-circular portion 39 which embraces the bushing 33 intermediate its side flanges 40, the free end of the resilient member or 30 spring 38 being secured to the opposite end of the bracket 34 by a bolt 41 having an eye portion 42 which pivots on a pin 43 secured to the bracket 34. It will be noted 35 that the free end of the spring is doubled back on itself at 44 and is provided with a slot 45 to permit the passage of a bolt 41. This bolt is provided with a nut 46 by means of which the spring member 38 may be adjusted to press yieldingly the distributing roll 16 in engagement with the inking rolls 15 to any desirable degree. By 40 bending the spring back on itself as at 44, resiliency of the connection is increased.

It will be noted that lugs 47 are provided 45 on the bracket 34 to prevent lateral movement of the resilient member 38. The semi-circular portion 39 of the resilient member 38 acts as a bearing for the bushing 33, and in order that the distributing roll may properly center or position itself with respect 50 to the inking rolls, I have provided the side members 36 of the bracket 34 with elongated slots 48 wherein the pin 37 may freely move back and forth to permit such centering 55 action. The slot 45 of the free end of the spring member 38 also permits the spring to move in a manner to permit the distributing roll properly to center itself with respect to the inking rolls. It will be noted 60 that in view of the fact that the member 38 is resilient, the distributing roll will be pressed into continuous engagement with the inking rolls in spite of any irregularities there may be in the surfaces of the inking rolls and at the same time the screw 65

may be adjusted to press the distributing roll into engagement with the inking rolls to any desired degree. The nut 46 also acts in a manner to hold the bushing 33 in the bracket 34 and hold all the parts intact.

The opposite end of the shaft 28 is provided with a bushing 49 which similarly is held by a resilient member or spring 50 similar to the other or spring member 38.

By referring to Figs. 1, 2, 5 and 6, it will 75 be noted that the distributing roll 18 is held in engagement with the single inking roll 17 by an arrangement similar to the one described in connection with the other figures of the drawings, the brackets 60 in this case lapping over the hooks 23 and being secured thereto by suitable screws 51. In this case, as well as in the case of the arrangement disclosed in connection with the other figures of the drawings, the distributing roll may be released by loosening the nut 46 and swinging the bolt 41 beyond the free end of the spring or resilient member 38. It will be noted that the resilient member 38 in Figs. 5 and 6 is pivotally mounted 80 on a pin 52 carried by the bracket 60. It will be noted, however, that no slot is provided in the bracket for the pin 52 for the reason that the distributing roll 18 does not have to center itself with respect to two 85 inking rolls. Otherwise the arrangement is substantially the same as disclosed in the other figures of the drawings.

It is well understood that the inking rolls are first moved over the inking surface of the disk 13 and then over the printing surface 14, and as a result of this movement the rolls are caused to rotate. The distributing roll is caused to rotate by its engagement with the inking rolls, and in view of the fact 100 that the distributing roll is each case is secured to its shaft, which is provided with a threaded portion 31, the distributing roll is caused to vibrate or reciprocate axially or longitudinally with respect to the inking 105 rolls. Normally the distributing roll 16, and therefore its shaft 28, rotates independently of the threaded bushing 33. However, if the inking rolls and the coöperating distributing roll 16 are rotated beyond a predetermined amount the bushing 33 will be caused to rotate with the distributing roll, the same being permitted in view of the fact 110 that the resilient member 38 engages the bushing 33 with only sufficient force to 115 normally frictionally hold the bushing; that is to say, when the limits of rotation of the rolls has not been reached the bushing 33 is held against rotation by the resilient member 38, but when the distributing roll is rotated beyond its normal limits the bushing 33 is permitted to rotate with the distributing roll.

It will be noted that the side flanges 40 of the bushing 33 are provided with cam por- 130

tions 53 and 54 which terminate in stops 55 and 56 respectively. It will also be noted that the outer end of the shaft 28 is provided with a pin 57 which is adapted to co-
 5 operate with the stop member 55 to limit independent movement of the distributing roller and its shaft with respect to the bushing 33 in one direction. The other end of the threaded portion 31 of the shaft 28 is
 10 provided with a pin 58 which is adapted to co-operate with the other stop 56 to limit independent movement of the distributing roll and its shaft 28 in an opposite direction. In other words, when the pin 57 passes into en-
 15 gagement with its corresponding stop 55 it causes the bushing 33 to rotate with the distributing roll in one direction, and when the other pin 58 passes into engagement with its corresponding stop 56 it causes the bushing
 20 33 to move in the opposite direction with the distributing roll, such movement being permitted due to the frictional engagement between the bushing 33 and the semi-circular portion of the spring or resilient member 38.
 25 In this manner the distributing roll is permitted freely to reciprocate or vibrate back and forth longitudinally with respect to the inking rolls, and if the inking rolls are run beyond certain predetermined limits in either
 30 direction the distributing roll may continue to rotate and thereby eliminate any disastrous results which otherwise might occur.
 It is apparent that there may be various modifications of the precise arrangement
 35 herein particularly shown and described, and it is my intention to cover all such modifications which do not involve a departure from the spirit and scope of the invention as set forth in the following claims.

40 I claim:

1. In a printing press, the combination of an inking roll, a distributing roll engaging the surface of said inking roll, and a resilient strip forming a portion of the roll
- 45 journal support for yieldingly holding said rolls in engagement with each other, the ends of said strip being restrained while permitting slight bodily movement of said strip.
- 50 2. In a printing press, the combination of an inking roll, a distributing roll engaging the surface of said inking roll, a shaft to which said distributing roll is secured and having a threaded portion, a threaded bushing co-operating with the threaded portion of said shaft whereby the distributing roll is caused to move axially, and a resilient strip forming a support for said bushing whereby said distributing roll is yield-
 55 ingly held in engagement with said inking roll.
- 60 3. In a printing press, the combination of an inking roll, a distributing roll engaging the surface of said inking roll, a shaft to which said distributing roll is secured
- 65 4. In a printing press, the combination of an inking roll, a distributing roll engaging the surface of said inking roll, and a shaft to which said distributing roll is secured

and having a threaded portion, a threaded bushing co-operating with the threaded portion of said shaft whereby the distributing roll is caused to move axially, and a resilient strip overlying said bushing and forming a support therefor and associated with said bushing to hold the same frictionally, whereby the distributing roll may have an axial movement therein. 70

4. In a printing press, the combination of an inking roll, a distributing roll engaging the surface of said inking roll, a shaft to which said distributing roll is secured and having a threaded portion, a threaded bushing co-operating with the threaded portion of said shaft whereby the distributing roll is caused to move axially, a resilient strip forming a bearing support and associated with said bushing to hold the same frictionally whereby the distributing roll 75 may have an axial movement therein, and means whereby said bushing may rotate with said distributing roll under certain conditions. 80

5. In a printing press, the combination of an inking roll, a distributing roll, and a resilient strip forming a bearing and adapted for holding said distributing roll in engagement with said inking roll, said strip being mounted with its ends restrained 85 while permitting bodily movement thereof. 90

6. In a printing press, the combination of an inking roll, a distributing roll, a resilient strip forming a bearing for holding said distributing roll in engagement with said inking roll, and means for adjusting said resilient strip for varying the degree of pressure with which said rolls engage 100 each other. 95

7. In a printing press, the combination of an inking roll, a distributing roll associated therewith, a shaft upon which said distributing roll is mounted, a bracket, and a member pivotally mounted in said bracket and serving as one portion of a bearing for 105 removably and yieldingly supporting said shaft. 110

8. In a printing press, the combination of an inking roll, a distributing roll, a shaft upon which said distributing roll is mounted, a bracket, and a resilient member pivotally mounted in said bracket for supporting said distributing roll and yieldingly pressing said distributing roll into engagement with said inking roll. 115 120

9. In a printing press, the combination of an inking roll, a distributing roll, a shaft upon which said distributing roll is mounted, a bracket, a resilient member pivotally mounted in said bracket for yieldingly pressing said distributing roll into engagement with said inking roll, and means associated with said bracket and resilient member for varying the pressure with which said rolls engage each other. 125 130

10. In a printing press, the combination of an inking roll, a distributing roll, a shaft upon which said distributing roll is mounted, a supporting member having a portion 5 for supporting said distributing roll, a member pivotally connected to said supporting member and removably supporting said distributing roll in engagement with said inking roll, said member having a 10 slotted portion, and a securing member movably mounted in said slotted portion to secure said member in a given position.

11. In a printing press, the combination of an inking roll, a distributing roll engaging the surface of said inking roll, a shaft upon which said distributing roll is mounted, a supporting member having an elongated slot therein, a pin mounted for movement in said slot, and a member pivotally 15 mounted on said pin and supporting said shaft, whereby the distributing roll is supported and is permitted to take a given position with respect to said inking roll.

12. In a printing press, the combination 20 of an inking roll, a distributing roll engaging the same and having a threaded shaft

portion, and a threaded bushing associated with the threaded shaft portion whereby the distributing roll may be given an axial movement, said bushing and shaft having 30 coöperating portions whereby said bushing may rotate with said distributing roll, said coöperating portions including a cam, and a flexible strip forming a support for the threaded bushing.

13. In a printing press, the combination of an inking roll, a distributing roll engaging the same and having a threaded shaft portion, and a threaded bushing associated with the threaded shaft portion whereby the 40 distributing roll may be given an axial movement, said bushing having oppositely arranged cams terminating in stops and the shaft having pins adapted to coöperate with said stops whereby said bushing may rotate 45 in opposite directions with said distributing roll, and a flexible strip forming a support for the threaded bushing.

Signed at Chicago, Illinois, this 6th day of August, A. D. 1917.

JOHN H. SCHUSSLER.
